A. E. PAIGE

PIPE CONVEYING MECHANISM

Filed Nov. 17, 1925

INVENTOR:

William E. Lacy

Patented May 4, 1926.

1,583,486

UNITED STATES PATENT OFFICE.

ARTHUR E. PAIGE, OF PHILADELPHIA, PENNSYLVANIA.

PIPE-CONVEYING MECHANISM.

Application filed November 17, 1925. Serial No. 69,633.

To all whom it may concern:

Be it known that I, ARTHUR E. PAIGE, a citizen of the United States, residing at Philadelphia, in the county of Philadelphia and State of Pennsylvania, have invented a certain new and useful Improvement in Pipe-Conveying Mechanism, whereof the following is a specification, reference being had to the accompanying drawings.

10 My invention may be employed with particular advantage in the manufacture of iron pipe in a rotary mold which is relatively axially movable with respect to a trough, through which the molten metal is poured; for instance centrifugal casting mechanism of the generic type described in my copending application Serial No. 62,947 filed October 17, 1925, for Letters Patent of the United States, wherein the mold is mounted to rotate upon a truck which is arranged to reciprocate upon a track. The purpose and effect of the present invention is to withdraw each, cast pipe from such a mold and discharge it upon tracks leading, transversely to said mold tracks, to an annealing furnace or other receiving means. However, the casting ejecting device herein disclosed is the subject matter of my copending application Serial No. 82,674 filed January 21, 1926, for 20 Letters Patent of the United States; the claims in this case being directed to the conveying mechanism which cooperates with said ejecting device to discharge the pipes laterally with respect to the axis of the mold.

25 The form of my invention hereinafter described is particularly adapted for use in cooperative relation with a mold adapted to cast pipes which have a bell at one end larger than the diameter of the pipe throughout the remainder of its length and includes supports which are counterpoised to gravitate to position to support the cast pipe but respectively pivoted, so that they may be temporarily tilted out of the path of the bell end of the pipe during the traverse of the mold to its position in which the pipe casting operation is completed; such tilting movement being conveniently effected by a roller carried by the mold truck and arranged to successively encounter and tilt said supports, out of the way of the mold and its truck.

As hereinafter described the axially movable mold carries the cast pipe, bell end forward, into engagement with a device, which, at the conclusion of the casting operation,

grapples the bell end of the pipe which is initially cast, so that as the axial movement of the mold is reversed, to return it to its initial casting position with respect to said trough; the cast pipe is withdrawn therefrom automatically, and, as the mold retreats from said grappling device, said tiltable supports successively automatically are upturned into position to support the pipe and direct it on its way to the tracks down which it is desired to discharge the pipe, to an annealing furnace or other receiving means.

My invention includes the various novel features of construction and arrangement hereinafter more definitely specified.

Fig. I is a fragmentary side view of a convenient form of apparatus embodying my invention, wherein the discharge tracks are sectioned on the line I, I in Fig. II.

Fig. II is a fragmentary transverse sectional view of said apparatus taken on the line II, II in Fig. I.

In said figures; a track 1 is formed of a pair of parallel rails, preferably inclined, and at an angle of four degrees to a horizontal plane. The truck frame 3 is provided with four supporting wheels 4 arranged to traverse said track. Said truck frame is conveniently formed of wrought steel including two opposite longitudinally extending channels 7 connected by cross channels 9 respectively at the front and rear ends thereof. Said cross channels 9 each support two roller bearing brackets 12, which are all alike. Said brackets 12 support two shafts 15 which are conveniently held stationary on said truck frame and support four mold bearing rollers 16 which are all alike. Said frame 3 and rollers 16 support the rotary mold 18 which has annular flanges 19 at its opposite ends engaging said rollers 16.

Said mold 18 is so constructed and arranged that the bell end pipe 26 may be rotarily cast therein and includes the tubular core 27 at the bell end of the mold, conveniently formed of a cementitious material carried by the circular plate 28 which is removably fitted in the end of the mold in which it is detachably secured by a pair of diametrically opposite tapered pins 30, which are removed at the end of each casting operation.

In order to prevent distortion of said mold 18; I provide means to subject it to the action of a refrigerant, preferably

water, and conveniently by surrounding said mold with the tank 32 which is held stationary on said truck frame 3 in coaxial relation with said mold, by two frame brackets 33 each provided with a strap bolt 35 with nuts 36. Said tank 32 has the cold water inlet 37 at the bottom thereof and the hot water outlet 38 at the top thereof, respectively connected with a cold water supply under pressure, and with a drain. In order to permit rotation of said mold in said tank without leakage of the water; I provide each end thereof with rings of packing in a stuffing box 40.

15 The circulation of refrigerant through said tank 32 may be controlled by controlling the passage of water through either said inlet 37 or outlet 38; so that the mold is continuously maintained at the proper 20 predetermined temperature during the casting operation.

Said mold 18 is continuously rotated during the casting operation, conveniently by means including an electric motor, driving 25 the shaft 42 carrying the gear 43 engaging the gear 44, at the remote end of the mold as seen in Fig. II.

The molten metal is directed into said mold by the pouring trough 47 which is 30 maintained relatively stationary, while said mold 18 is rotated and reciprocated with respect thereto. The movement of reciprocation of said mold may be conveniently effected by a screw thread on said shaft 42 35 engaging a nut 48 held stationary on said truck frame 3, as described at length in my copending application aforesaid. However, it is to be understood that said mold may be axially reciprocated upon said tracks 1 by 40 any convenient means applied to said truck 3; the latter being gradually shifted to the right in Fig. I during each casting operation, and being returned to the position in which it is shown, at the left of Fig. I, 45 before the initiation of the next succeeding casting operation.

A suitable pipe grappling device, for instance including the rotatable axial support 152 carrying the levers 153 and 154, connected by the links 155, is detachably supported in the standard bearing 156 (which is in rigid relation with said tracks 1 at the right hand end thereof) and is initially in inoperative position, with the lever 154 inclined. However, movement of said truck 3 55 with the mold 18 and cast pipe 26 to the right in Fig. I brings the right hand end of the mold against said lever 154, erecting it and thus spreading said links into engagement with the core 27; while said support 152 is journaled in said bearing 156 between its collars 158 and 159, to temporarily hold said pipe 26 while the mold is being withdrawn therefrom, toward the left in Fig. 60 I; for instance, by reversal of rotation of

said shaft 42; thus leaving the cast pipe 26 in engagement with said grappling device as shown in Fig. I.

However, it is obvious that said pipe would fall of its own weight when released 70 from the mold, as it passes to the position shown in Fig. I, if means were not provided to otherwise support it.

As shown; the means for supporting the pipe 26, so as to uphold it in axial alignment 75 with said mold 18, as indicated in Fig. I; includes two similar pivoted struts 161 and 162 which are adapted to be successively tilted to the right in Fig. I, out of the way of the truck 3 and the apparatus carried by 80 the latter, by means of the roller 163 which is mounted upon the right hand end of said truck. Said struts are respectively pivoted upon trunnions 164 which are journaled in bearing brackets 165 which are conveniently 85 rigidly connected with the respective rails of the track 1; the latter being held in proper spaced relation by bolts 167 provided with nuts 168 upon opposite sides of the vertical webs of said rails, as best shown in Fig. II. 90 Said struts 161 and 162 have respective counterweights 169 by which they are normally upturned to the position shown in Fig. I, whenever they are successively released, from their down tilted position, by 95 the passage of said truck 3 toward the left in Fig. I. In such upturned position, said struts rest against the respective bolts 167. In order to insure that the weight of said pipe 26 shall cause said struts 161 and 162 100 to remain upright, in contact with said bolts 167, during the discharging operation, instead of tilting to the right in Fig. I, away from said bolts 167, I incline the upper edges of said struts 161 and 162 to the left 105 in Fig. I; in which position the center of gravity of each of said struts is upon the left hand side of its axis and said struts are in cooperative relation with the discharging track formed of two parallel rails 170 which 110 are rigidly supported in any convenient manner and are preferably downwardly inclined away from said struts and toward an annealing furnace 171 or other means for receiving said pipes 26. Each pipe 26 is 115 normally detained in coaxial relation with said mold 18 in depressions 173 in the tops of said struts from which each pipe may be rolled aside by manipulation of said lever 154. Said grappling support 152 being then 120 released from the bearing 156 may be released from said pipe 26 by returning said lever 154 to its initial position in the support 156, and the core plate 28 and core 27 knocked loose from the pipe. Thereupon, 125 the operation may be repeated as above described.

Although I have illustrated my invention with reference to centrifugal casting mechanism of a specific form adapted for casting 130

bell end pipe; it is to be understood that I do not desire to limit myself thereto; as other forms of molds may be employed in conjunction with the discharging apparatus above described; which is adapted to receive 5 pipes from any suitable carrier.

Therefore, I do not desire to limit myself to the precise details of construction, arrangement and procedure herein set forth, 10 as it is obvious that various modifications may be made therein without departing from the essential features of my invention as described in the appended claims.

I claim:

1. The combination with means arranged 15 to shift a bell end pipe axially; of pipe conveying mechanism, including a plurality of struts extending transversely to the axis of said pipe and independently pivoted upon 20 axes transverse to the pipe axis and respectively provided with counterbalance weights; whereby said struts are arranged to gravitate to upright position to support the pipe, but may be temporarily tilted out of 25 the path of the pipe during its traverse to the axial position in which it is to be received upon said struts; each of said struts having a shallow depression adapted to receive and prevent accidental displacement 30 of the pipe; and stop means limiting the tilting movement of said struts to upright position; the upper ends of said struts being respectively extended beyond vertical planes intersecting their centers of gravity 35 and toward said stop means; whereby the weight of said pipe holds said struts against said stop means.

2. The combination with means arranged 40 to shift a pipe axially; of pipe conveying mechanism, including a plurality of counterbalanced struts extending transversely to the axis of said pipe and independently pivoted upon axes transverse to the pipe axis; whereby said struts are arranged to gravitate 45 to upright position to support the pipe, but may be temporarily tilted out of the path of the pipe during its traverse to the axial position in which it is to be received upon said struts; each of said struts having means adapted to receive and prevent accidental displacement of the pipe; and stop 50 means limiting the tilting movement of said struts to upright position; the upper ends of said struts being respectively extended beyond vertical planes intersecting their 55 centers of gravity and toward said stop means; whereby the weight of said pipe holds said struts against said stop means.

3. The combination with means arranged 60 to shift a pipe axially; of pipe conveying mechanism, including a plurality of counterbalanced struts extending transversely to the axis of said pipe and independently pivoted upon axes transverse to the pipe axis;

whereby said struts are arranged to gravitate 65 to upright position to support the pipe, but may be temporarily tilted out of the path of the pipe during its traverse to the axial position in which it is to be received upon said struts; each of said struts having 70 means adapted to receive and prevent accidental displacement of the pipe; and stop means limiting the tilting movement of said struts to upright position.

4. The combination with means arranged 75 to shift a pipe axially; of pipe conveying mechanism, including a pivoted and counterbalanced strut extending transversely to the axis of said pipe; whereby said strut is arranged to gravitate to upright position to support the pipe, but may be temporarily tilted out of the path of the pipe during its traverse to the axial position in which it is to be received upon said strut; said strut having a shallow depression in its top 80 adapted to receive and prevent accidental displacement of the pipe; stop means limiting the tilting movement of said strut to a position in which it is overbalanced against 85 said stop means; whereby the weight of said pipe holds said strut against said stop means.

5. The combination with means arranged 90 to shift a pipe axially; of pipe conveying mechanism, including a pivoted and counterbalanced strut extending transversely to the axis of said pipe; whereby said strut is arranged to gravitate to upright position to support the pipe, but may be temporarily tilted out of the path of the pipe during its 95 traverse to the axial position in which it is to be received upon said strut; said strut having means adapted to receive and prevent accidental displacement of the pipe; stop means limiting the tilting movement of said strut to a position in which it is overbalanced against 100 said stop means; whereby the weight of said pipe holds said strut against said stop means.

6. The combination with means arranged 105 to shift a pipe axially; of pipe conveying mechanism, including a pivoted and counterbalanced strut extending transversely to the axis of said pipe; whereby said strut is arranged to gravitate to upright position to support the pipe, but may be temporarily tilted out of the path of the pipe during its 110 traverse to the axial position in which it is to be received upon said strut; stop means limiting the tilting movement of said strut to a position in which it is overbalanced against 115 said stop means; whereby the weight of said pipe holds said strut against said stop means.

In testimony whereof, I have hereunto signed my name at Philadelphia, Pennsylvania, this fourteenth day of November, 125 1925.

ARTHUR E. PAIGE.
